UNITED STATES PATENT OFFICE

150,298

DESIGN FOR A SUN WATCH

John E. Johanson and Francis O. Boyd,
Boonton, N. J.

Application January 29, 1947, Serial No. 136,496

Term of patent 14 years

(Cl. D42—8)

To all whom it may concern:

Be it known that we, Francis O. Boyd and John E. Johanson, citizens of the United States, residing in Boonton, county of Morris and State of New Jersey, have invented a new, original, and ornamental Design in Sun Watches, of which the following is a specification, reference being had to the accompanying drawing, forming part thereof.

Fig. 1 is a perspective view of a sun watch in a closed condition;

Fig. 2 is a perspective view, on a somewhat larger scale than Fig. 1, showing our new design partially opened; and

Fig. 3 is a top plan view, on a still larger scale showing said sun watch after it has been opened to the extent of bringing the two halves of the watch casing into the same plane.

We claim:

The ornamental design for a sun watch, as shown and described.

JOHN E. JOHANSON.
FRANCIS O. BOYD.
